Inventor:

William V. Holley

By his Attorneys:

Philip Sawyer Rice Kennedy

UNITED STATES PATENT OFFICE.

WILLIAM V. HOLLEY, OF NEW YORK, N. Y., ASSIGNOR TO NEW YORK BATH MANUFACTURING CO., A CORPORATION OF NEW YORK.

SERVICE BOX OR TRAY.

1,426,079.

Specification of Letters Patent. Patented Aug. 15, 1922.

Application filed March 9, 1920. Serial No. 364,585.

To all whom it may concern:

Be it known that I, WILLIAM V. HOLLEY, a citizen of the United States, residing at New York, county of New York, and State 5 of New York, have invented certain new and useful Improvements in Service Boxes or Trays, fully described and represented in the following specification and the accompanying drawings, forming a part of the 10 same.

This invention relates to improvements in service boxes or trays used for carrying large numbers of used dishes in hotel dining rooms and like places.

15 In these boxes as heretofore constructed the bottom was secured to the side walls by suitable securing devices, as screws or nails, inserted at intervals around the edges of the box. Due to the hard usage to which these 20 boxes are subjected, the screws or nails used for securing the bottoms to the boxes have become loosened and fall out, and furthermore, the boxes, particularly where made of wood, would sag at the joints and become 25 unfit for service.

It is the particular object of the present invention to provide an improved dish box or tray in which the bottom of the box is reinforced and the screws or nails by which 30 the bottom is secured to the side walls are covered so that the box is strengthened, and the nails or screws are prevented from dropping out if they become loosened.

A further object of the invention is to produce a strong, cheap and durable dish box or tray.

With these and other objects not specifically referred to in view, the invention consists in certain novel parts and constructions which will be described in connection with the accompanying drawings and then specifically pointed out in the claims hereunto annexed.

Referring now to these drawings,—

45 Figure 1 is a perspective view of the improved box shown right side up;

Figure 2 is a similar view showing the box inverted;

Figure 3 is a bottom plan view of the 50 box showing the reinforce and the means for covering the nails or screws before these means are turned to covering position.

Figure 4 is a view similar to Figure 3 showing the covering means turned to their 55 final position; and

Figures 5 and 6 are detail sectional views taken on the line 5—6 of Figure 4 showing on an enlarged scale the improved means for covering the nails or screws before and after turning in place. 60

Referring now to these drawings, the improved dish box or tray may be made of any suitable material, such as wood fibre, or metal. In the particular construction illustrated, it is made of wood and is formed with 65 a bottom 1, side walls 2 and end walls 3, the end walls being provided with hand holes 4 by which the box may be readily grasped by the hand.

The bottom is secured to the side walls by 70 suitable securing means, which in the present instance are screws 5. These screws are, as shown in Figure 3, provided in sufficient numbers around the edges of the box to insure the secure holding of the bottom to the 75 walls.

In the best constructions, particularly where the box is of wood, a metal reinforcing plate 6 is employed, this plate preferably 80 extending over the whole bottom surface of the box as shown and being secured to the bottom of the box by the securing screws 5 which pass through it, as shown in Figures 5 and 6, though if desired this reinforcing plate may be omitted. 85

The invention provides means for covering the screws so that they will not fall out if they become loosened and these means may vary somewhat in character. In a preferred construction, for simplicity and 90 cheapness, where the metal plate 6 before referred to is employed, this plate will be used for this purpose. As shown, the plate 6 is dimensioned larger than the bottom of the box to form end flanges 7 and side 95 flanges 8, the plate being cut away at the corners as indicated at 9, these flanges 7 and 8 extending beyond the edges of the bottom of the box. After the plate has been secured to the box as before described, the 100 flanges 7 and 8 are bent or turned over into the plate so as to lap over the heads of the screws to produce the structure shown in Figure 2, the plate being of metal sufficiently thick, so that when the flanges 105 are turned over they will retain their turned over position without further securing means. The cut away corners of the plate permit this bending and allow the flanges to be turned over so as to have smooth joints. 110

Where, as shown, the reinforcing plate is used these turned in flanges provide a further reinforce and make a very rigid and desirable structure.

- 5 If desired corner plates 10 may be provided, which are put in position before the flanges are turned over and held at the corner points by the screws 5 before referred to.
- 10 With the construction shown and described a very strong and durable box is provided and one in which the screws or nails used for securing the parts together cannot drop out if they become loosened
- 15 and thus weaken the box, and the box is furthermore reinforced by the screw covering means so as to provide a rigid structure in which the bottom is not liable to sag away from the walls.
- 20 While the way shown and described for covering or protecting the means for securing the parts together is a convenient one, it will be understood that certain changes and variations may be made in the
- 25 means for thus covering the screws, and that such changes can be made without departing from the invention.

What is claimed is:

1. A service box or tray having side walls and a bottom and means for fastening the bottom to the walls, a metal reinforce ex-

tending entirely around the bottom and projecting beyond the edges thereof and secured to the bottom by the fastening means and subsequently folded inwardly to overlie the fastening means to prevent displacement thereof, in addition to accomplishing its reinforcing purposes. 35

2. A service box or tray having side walls and a bottom, a metal plate, fasteners securing the plate to the bottom and the bottom to the side walls, said plate being of greater dimensions than the bottom to provide flanges which are turned in over the heads of the fasteners subsequent to the application thereof to prevent displacement thereof. 40

3. A service box or tray having side walls and a bottom, screws securing the side walls and bottom together, a metal plate secured to the bottom by said screws, said plate being of greater dimensions than the bottom to project beyond the edges thereof and being cut at the corners to constitute flanges, the flanges being folded inwardly upon themselves to overlie the screws so as to prevent displacement thereof, and corner plates held in position by the flanges. 45 50 55

In testimony whereof, I have hereunto set my hand.

WILLIAM V. HOLLEY.
